UNITED STATES PATENT OFFICE.

FRED HURBERT SHORT, OF WATERVILLE, MAINE.

HEATING PLANT.

1,398,921.

Specification of Letters Patent.

Patented Nov. 29, 1921.

Application filed June 12, 1920. Serial No. 388,512.

To all whom it may concern:

Be it known that I, FRED HURBERT SHORT, a citizen of the United States, residing at Waterville, in the county of Kennebec and 5 State of Maine, have invented certain new and useful Improvements in Heating Plants, of which the following is a specification.

This invention relates to heating plants and has for an object to provide a device 10 for employing fluid fuel with improved means for volatilizing, oxidizing and igniting the fuel.

A further object of the invention is to provide an improved form of burner for advancing and igniting the gaseous product of volatilization.

Further object of the invention is to provide a retort positioned in improved location relative to the burners whereby a more complete and attenuated volatilization is accomplished.

With these and other objects in view the invention comprises certain novel units, parts, elements, combinations and arrangements as will be hereinafter more fully described and claimed.

Referring to the accompanying drawing which is made a part hereof and on which similar reference characters indicate similar 30 parts,

Figure 1 is a view of the improved heating plant somewhat diagrammatically shown in side elevation with parts broken away to show the internal construction,

35 Fig. 2 a top plan view of the burner area, and

Fig. 3 a vertical, diametrical, sectional view through one of the burner units.

The improved heating plant, which forms 40 the subject matter of this application, comprises a base 10 supported in any approved manner, but preferably by a support 11 in the form of a housing or casing. Into the housing or casing 11 a pipe 12 is inserted 45 having a funnel or hopper-like upper extremity 13 corresponding substantially with the burner area defined by the marginal wall 14. Communicating with the pipe 12 is a fan blower 15 operated in any approved manner, as by an electric motor, conventionally 50 shown at 16.

The base 10 is properly drilled and tapped to receive a plurality of burner units 17 55 preferably arranged in rows, as indicated at Fig. 2. The arrangement of the burner units

in this form permits the retort coil 18 to take the form of a spiral having nearly square turns at the several corners with the outlet extremity at 19 directed downwardly substantially through the center of the 60 base 10.

Communicating with the retort 18 is a pipe 20 which passes down substantially in U-shape to the lower section 21 and again upwardly, as at 22 and communicates with 65 a gravity supply tank 23. The position of the several parts just described is such that fluid fuel from the tank 23 will flow through the sections 22, 21 and 20 of the inlet pipe into the retort 18 positioned throughout its 70 entire length above successive rows of burner units.

Where the extremity of the retort is inserted through the base 10 as at 19 it is provided with a perforated section 24 from 75 which the gaseous product of volatilization in the retort is discharged laterally into the hopper 13 where it commingles with the air produced by the fan blower 15 and is thereby forced upwardly through the burner units. 80

Each of the several burner units comprises a substantially spherical head 25 (see Fig. 3) which for convenience will be provided with a multiangular lug 26 which permits the application of a wrench thereto for insertion of the burner into and removal from the base 10. The spherical head 25 of the burner unit is provided with a series of substantially equatorial perforations 27 and a series of perforations 28 located above the 90 perforations 27 and directed downwardly so that the discharge from the perforations 27 and 28 will cross, as at 29.

It is desirable to provide the plant with automatic means for shutting off the fuel and current to the fan motor in case of failure to volatilize or imperfect volatilization from any cause, as for instance, the accidental extinguishing of the flame at the burners. This comprises a drip funnel 30 located immediately beneath the perforated section 24 and in communication with a pipe 31 which leads to and discharges into a drip cup 32. The latter controls the fuel supply through the medium of the valve 33 to which the drip cup 32 is attached by the link 34, such link being also connected with the switch 35 which is positioned in the circuit, indicated at 36. When, by reason of discharge of fluid fuel through the perforated section 24, 105

the structure just described causes the fuel to flow into the drip cup 32 and by applying the weight of such fuel causes the drip cup to fall closing the valve 33 and opening the switch 35 whereby the flow of fuel is discontinued and current to the motor is interrupted.

It is believed that the operation of the plant will be thoroughly and completely understood from the foregoing without further statement specifically directed to the operation.

Having thus fully described my said invention what I claim as new and desire to secure by Letters Patent, is:

1. A heating plant comprising, a supporting structure embodying a substantially horizontal base, a plurality of burner units inserted through the base, an air conduit 20 communicating with the under side of the base, a retort located above the burners and discharging through the center of the base into the air conduit and means to supply air to the conduit.

25 2. A heating plant comprising, a supporting structure embodying a base, a plurality of burner units disposed above the base and having communication with the under side of the base, an air conduit disposed beneath the base and in communication with the several burner units, a retort located above the burners extending downwardly through the center of the base and discharging immediately below the base into the air conduit, 35 means to supply air to the conduit, and means to supply fluid fuel to the retort.

3. A heating plant comprising, a base embodying a plate, a plurality of burner units arranged above the plate in geometrical relation and communicating with the under side of the plate, a retort in the form of a pipe bent to correspond to the geometrical arrangement of the burner units located above such units extending through the center of the base and discharging slightly below the same, an air conduit arranged below the base embracing the discharge from the retort and communicating with the burner units and means to supply air to the conduit.

40 4. A heating plant comprising, a supporting structure, a substantially spiral retort pipe disposed above the supporting structure, burner units disposed in spiral arrangement each burner being beneath the sinuous retort, an air conduit communicating with the burners and means forming a downward extension of the retort at the center of the spiral discharging into the air conduit.

45 5. A heating plant comprising, a supporting structure embodying a plate, a sinuous retort pipe located above the plate and terminating with a section inserted substantially through the center thereof, a plurality of burner units erected above the plate disposed immediately beneath the retort con-

volutions, an air conduit disposed beneath the plate communicating with the burner units and an extensor for the retort discharge extremity comprising means to discharge a plurality of jets into the air conduit. 70

6. A heating plant comprising, a supporting structure embodying a plate, an air conduit disposed beneath the plate and terminating in an enlargement beneath the plate, a retort pipe spaced above the plate and formed in a plurality of convolutions extending downwardly substantially through the center of the plate and discharging into the enlargement of the air conduit, and a 75 plurality of burner units erected above the plate and immediately beneath the convolution of the retort and in communication with the air conduit.

7. In a heating plant, a burner unit comprising a riser, a spheroidal head formed upon the riser, equatorial perforations formed about the spheroidal head and other perforations spaced from the equatorial perforations directed to transect the plane of 90 the equatorial perforations.

8. In a heating plant, a burner unit comprising a tubular riser, a hollow spheroidal head communicating with the riser, a series of spaced equatorial perforations formed 95 about the spheroidal head in a substantially horizontal plane and a series of perforations through the spheroidal head above the equatorial perforations directed downwardly to transect the plane of the equatorial perforations at a circumference spaced away from the periphery of the head.

9. A heating plant comprising burners, means to force air into the burners, means to inject volatilized liquid fuel into the air 105 supply adjacent the burners, and means to stop the supply of fuel on imperfect volatilization thereof, substantially as set forth.

10. A heating plant comprising burners, 110 means to force air into the burners, means to inject volatilized liquid fuel into the air supply adjacent the burners, and means to stop the supply of fuel and air on imperfect volatilization of the fuel, substantially as 115 set forth.

11. A heating plant comprising burners, means to force air into the burners, means to inject volatilized liquid fuel into the air adjacent the burners and means to stop the 120 supply on imperfect volatilization thereof comprising a valve in the fuel supply pipe, a receptacle adapted to receive unvolatilized fuel and connections from the receptacle to the valve to close the same as the receptacle 125 is filled, substantially as set forth.

12. A heating plant comprising burners, a motor to force air into the burners, means to inject volatilized liquid fuel into the air adjacent the burners and means to stop the 130

supply of fuel on imperfect volatilization thereof comprising a valve in the fuel supply pipe, means adjacent the end of the pipe to receive unvolatilized fuel and connections 5 therefrom adapted to close the valve and stop the motor as the supply of fuel accumulates, substantially as set forth.

13. In a heating device, a plate, burners mounted on the plate, a conduit below the 10 plate for supplying air to the burners, a supply pipe for liquid fuel extending over the burners and thence into the air conduit to supply volatilized fuel to the air, means adjacent the end of the pipe for collecting un- 15 volatilized fuel and means connected thereto for automatically stopping the flow of fuel on imperfect volatilization thereof, sub- stantially as set forth.

14. In a heating device, a plate, burners 20 mounted on the plate, a conduit below the plate for supplying air to the burners, a supply pipe for liquid fuel extending over the burners and thence into the air conduit to supply volatilized fuel to the air, means adjacent the end of the pipe for collecting unvolatilized fuel and means connected thereto for automatically stopping the flow of fuel on imperfect volatilization thereof, said means also cutting off the supply of air, 25 substantially as set forth.

15. In a heating system, a plate, burners mounted thereon, means communicating with the underside of the plate to supply air to the burners, said means including a fan, 30 a pipe to supply volatilized liquid fuel to said means, an electric motor to drive the fan, and means acting on imperfect volatili- zation of the fuel to cut off the supply and

to break the motor circuit, substantially as set forth.

16. In a heating system, a plate, burners mounted thereon, means communicating with the underside of the plate to supply air to the burners, said means including a fan, a pipe to supply volatilized liquid fuel to 45 said means and an electric motor to drive the fan, and means acting on imperfect volatilization of the fuel to cut off the supply and break the motor circuit, said means comprising a cup, means adjacent to the fuel 50 pipe to catch unvolatilized fuel and lead it to the cup, a valve in the fuel pipe, a switch in the motor circuit and a link suspended from the handles of the switch and the valve and carrying said cup, substantially as 55 set forth.

17. In a heating system, a plate, burners on the plate, means underneath the plate to supply air to the burners, a fuel supply pipe extending over the burners and downward through the plate into the air supply- 60 ing means, a portion of the pipe below the plate being perforated, a funnel under the perforated portion, a cup connected to such portion, and means connected to the cup for 65 stopping the flow of fuel as the cup fills, substantially as set forth.

In witness whereof, I have hereunto set my hand and seal at Waterville, Maine, this 7th day of June, A. D. nineteen hundred 70 and twenty.

FRED HURBERT SHORT.
